CENTERLESS GRINDING OF ELONGATED
ROLLERS THAT ARE CURVED LENGTH-
WISEAlton H. Lundius, East Orange, N. J., assignor to
General Motors Corporation, Detroit, Mich., a
corporation of Delaware

Application May 1, 1947, Serial No. 745,333

11 Claims. (Cl. 51—79)

1

This invention relates to the centerless grinding of elongated rollers that are curved lengthwise and comprises all of the features of novelty herein disclosed. An object of the invention is to provide improved mechanism for generating an arcuate longitudinal curvature on elongated rollers such as barrel shaped rollers for self-aligning bearings. Another object is to provide a centerless grinding machine which will act with greater speed and less idle time than previous machines for the purpose. To these ends and also to improve generally upon machines of this character, the invention consists in the various matters hereinafter described and claimed. In its broader aspects the invention is not necessarily limited to the specific construction selected for illustrative purposes in the accompanying drawings in which

Fig. 1 is a plan view with parts in horizontal section below the upper work blade.

Fig. 2 is a front elevation.

Fig. 2A is a central sectional view of portions of the wheels and the work blades, the work piece being enlarged.

Fig. 3 is a perspective view of the moving parts of the roller feeding mechanism.

Fig. 4 is a plan view of the upper blade and its holder.

Fig. 5 is a front view of a loading block.

Fig. 6 is a side view of the machine, the wheels and part of the feeding mechanism being removed.

Fig. 7 is a plan view of the base plate.

Fig. 8 is a front view of Fig. 7.

Fig. 9 is a plan view of the lower blade holder.

Fig. 10 is a front view of Fig. 9.

The rollers W, herein shown as of the elongated type curved lengthwise such as symmetrical barrel shaped rollers, are ground by a concave or transversely curved grinding wheel G along which they travel endwise in an arc while rotated and advanced by a regulating wheel R which has a spiral groove 2 and a spiral rib 4 with a plurality of turns. The bottom of the groove is curved to fit the rollers and form a seat therefor. Since the curve of the groove and the curvature of the grinding wheel are directly opposed, the rollers are self-centering and do not depend on the sides of the rib to advance them. The regulating wheel is secured to a flanged hub 6 by a flanged nut 8 and is rotated upwardly at the work by a shaft 10. A cam 12 having arcuate slots 14 is adjustably secured to the regulating wheel by screws. As will later appear, this cam controls the feeding of the rollers to the regulat-

2

ing wheel. As the rollers travel endwise between the wheels, they are loosely confined for rotation between a curved upper blade 16 (Fig. 6) and a curved lower blade 18. The lower surface of the upper blade except at one end slants downwardly away from the regulating wheel and the upper surface of the lower blade slants downwardly towards the regulating wheel. The blades have work guiding surfaces which extend beyond the sides of the wheels and their length is greater than that of a plurality of rollers.

The upper blade is clamped to a curved blade holder 20 by clamping plates 22 each having a little lip engaging the blade holder next to a shoulder and a slanting edge engaging the end of the blade. The blade holder has a slotted extension secured by screws 24 in a groove of an upright standard 26 secured by a key or projection 28 and bolts to one vertical edge of a flange or web 30 on base plate 32. In order that the rollers may be introduced laterally or sidewise between the blades into the spiral groove of the regulating wheel from one side of the grinding wheel, the upper blade is cut away at 34 adjacent to one end to form a roller passage and another portion is cut away at 36 to clear the feeding mechanism. Between the wheels, the adjacent edges of the blades are closer together than the diameter of the rollers and they present bevelled roller confining edges towards the regulating wheel. The grinding wheel is slabbed off or narrower than the regulating wheel to provide space for the feeding mechanism and to expose a turn of the spiral groove. The center of transverse curvature of the grinding wheel lies in the central plane of the regulating wheel and hence the grinding wheel is unsymmetrical. The blade curvature has the same center of curvature and both blades fit up close to the grinding wheel.

The lower blade 18 is supported and adjusted vertically by a stud 38 threaded in the base plate, the blade then being secured by clamping plates 40 to a saddle or blade holder 42. Each clamping plate has a little lip (Fig. 1) engaging the blade holder next to a shoulder and a slanting edge to engage the end of the arcuate blade. The blade holder is located vertically by two pins 44 projecting from the flange or web 30, the blade holder being secured to the web by screws 45 passing through countersunk holes 45 into tapped holes in the web. To clear the grinding wheel, the web 30 is notched at 46 and its rear face is steeply inclined below the notch. The blade holder has a similar clearance notch at 47 with the rear face similarly inclined. An opening 48

3

in the web provides for access to one of two vertical bolts 49 by which the base plate is adjustably secured to the frame of a centerless grinder (not shown), the bolts passing down through slots in the base plate into the frame.

The rollers W are urged endwise through an inclined feed tube 50 from which they enter a hole in a loading block 52 and pass into a loading groove or roller locating recess 54 where the rollers in succession impinge against a hardened stop plate 56. This locates the endmost roller in alignment with the spiral groove of the regulating wheel before being pushed into the groove sidewise through the roller passage at 34 in the upper blade. The loading block has a bottom tongue entering a groove in a horizontal projection 58 on a vertical standard 60 which has a locating tongue or key entering a vertical groove 61 in the web 30, the standard being secured in vertically adjusted position by screws 62.

The rollers are pushed sidewise in succession from the loading groove 54 by an oscillating feeding finger 64 whose shank is slotted and adjustably clamped by a screw 66 in a groove of an angular bracket 68. The upper leg of the bracket 68 is slotted and adjustably secured by screws 70 to a horizontal face on a support 72 which has a flattened vertical shank 73 pivoted at 74 between flanges on a vertical lever arm 76. The support 72 is urged against a shoulder on the lever arm by a coil spring 80 which surrounds a threaded stud 82 passing through a vertical slot in the support 72 and fixed to the lever arm. The spring is interposed between the support and an adjusting nut and can give to allow the support to swing around its pivot in case the rollers get jammed. The lever arm forms part of a bell crank lever which is pivoted at 84 between lugs projecting at an angle from a bracket 86 which has four attaching ears secured by screws to the web 30. The horizontal arm of the bell crank lever is bent at the end and carries a cam roll 88 running on the above mentioned cam 12 which rotates with the regulating wheel. The cam roll is held against the cam by a coil spring 90 which is anchored to a bent bracket 92 fastened to the top of the web 30.

At each revolution of the regulating wheel and the cam, the feeding finger advances and a roller is pushed from the loading groove 54 over the lower blade into the spiral groove 2 of the regulating wheel. The pitch of the groove and the rotation of the regulating wheel cause the roller to advance endwise along the blades and between the wheels for centerless grinding. Since there are several turns to the spiral groove, a plurality of rollers are simultaneously in engagement with the wheels and there is no idle time.

I claim:

1. In a machine for grinding rollers that are curved lengthwise, a regulating wheel having a spiral groove the bottom of which is curved to fit the rollers, a grinding wheel having an arcuate contour transversely, the center of curvature being substantially in the central plane of the regulating wheel, one side of the grinding wheel being slabbed off to make it unsymmetrical and narrower than the regulating wheel to expose the spiral groove, a curved work blade immovably fixed between the wheels and conforming to the curve of the grinding wheel, said blade having a work guiding surface of a length greater than the width of the grinding wheel, means for introducing rollers one at a time into the groove, and means for rotating the regulating wheel to cause

4

the spiral groove to push the rollers endwise along the fixed blade.

2. In a machine for grinding rollers that are curved lengthwise, a regulating wheel having a spiral groove the bottom of which is curved to fit the rollers, a grinding wheel having an arcuate contour transversely, the center of curvature being substantially in the central plane of the regulating wheel, one side of the grinding wheel being slabbed off to make it unsymmetrical and narrower than the regulating wheel to expose the spiral groove, a curved work blade fixed between the wheels and having substantially the same center of curvature as the transverse contour of the grinding wheel, means for rotating the regulating wheel to cause the spiral groove to push the rollers endwise along the fixed blade, and means controlled by every revolution of the regulating wheel for pushing one roller laterally into the spiral groove from the slabbed off side of the grinding wheel.

3. In a machine for grinding rollers that are curved lengthwise, a regulating wheel having a spiral groove the bottom of which is curved to fit the rollers, a grinding wheel having an arcuate contour transversely, the center of curvature being substantially in the central plane of the regulating wheel, a curved work blade immovably fixed between the wheels and conforming closely at its edge to the curve of the grinding wheel, said blade having a work guiding surface extending from one side of the regulating wheel to the other, means for rotating the regulating wheel to cause the spiral groove to push the rollers endwise along the fixed blade, and means for introducing rollers one at a time into the groove, the groove having a plurality of turns so that a plurality of rollers are simultaneously advanced along the grinding surface of the fixed blade by the groove.

4. In a machine for grinding rollers that are curved lengthwise, a regulating wheel having a spiral groove the bottom of which is curved to fit the rollers, a grinding wheel having an arcuate contour transversely, upper and lower blades between the wheels and each curved to conform closely to the curve of the grinding wheel, the adjacent edges of the blades being slanted to present bevelled roller engaging edges toward the regulating wheel and one of said edges having a cut-away portion at one end to provide a passage larger than a roller, means for introducing rollers through said passage to the spiral groove, and means for rotating the regulating wheel to cause the spiral groove to push the rollers endwise along the blades and the grinding wheel.

5. In a machine for grinding rollers that are curved lengthwise, a regulating wheel having a spiral groove the bottom of which is curved to fit the rollers, a grinding wheel having an arcuate contour transversely, one side of the grinding wheel being slabbed off to make it unsymmetrical and narrower than the regulating wheel to expose the spiral groove, upper and lower curved blades between the wheels, the edges of the blades being slanted to present roller confining edges towards the regulating wheel and one of said edges having a cut-away portion at one end to provide a roller passage, means for rotating the regulating wheel, and means controlled by every revolution of the wheel for pushing one roller laterally through the passage into the spiral groove from the slabbed off side of the grinding wheel.

6. In a machine for grinding rollers that are curved lengthwise, a regulating wheel having a

spiral groove with a plurality of turns, a grinding wheel having an arcuate contour transversely, a curved work blade fixed between the wheels and conforming at its upper edge to the curvature of the grinding wheel, means for rotating the regulating wheel to cause the spiral groove to push a plurality of rollers simultaneously along the blade, and means for introducing a roller over the blade into the groove at every revolution of the regulating wheel.

7. In a machine for grinding rollers that are curved lengthwise, a regulating wheel having a spiral groove with a plurality of turns, a grinding wheel having an arcuate contour transversely, a curved work blade fixed between the wheels and conforming at its upper edge to the curvature of the grinding wheel, means for rotating the regulating wheel to cause the spiral groove to push a plurality of rollers simultaneously along the blade, a loading block having means to locate the rollers endwise in succession with their peripheries in alignment with the spiral groove, and means actuated by every revolution of the regulating wheel for pushing a roller sidewise into the spiral groove from the loading block.

8. In a machine for grinding rollers that are curved lengthwise, a regulating wheel having a spiral groove with a plurality of turns, a grinding wheel having an arcuate contour transversely, a curved work blade fixed between the wheels and conforming at its upper edge to the curvature of the grinding wheel, means for rotating the regulating wheel to cause the spiral groove to push a plurality of rollers simultaneously along the blade, a loading block having a roller locating groove adjacent to the spiral groove, a feeding finger movable through the loading groove, and a cam fixed to the regulating wheel for oscillating the feeding finger to push a roller sidewise from the loading groove into the spiral groove at every revolution of the regulating wheel.

9. In a machine for grinding rollers that are curved lengthwise, a regulating wheel having a spiral groove with a plurality of turns, a grinding wheel having an arcuate contour transversely, a curved work blade fixed between the wheels and conforming at its upper edge to the curvature of

the grinding wheel, means for rotating the regulating wheel to cause the spiral groove to push a plurality of rollers simultaneously along the blade, a loading block having a roller locating recess, a feed tube for conducting rollers endwise into the recess, a feeding finger in alignment with the recess, a bell crank lever supporting the finger, and a cam fixed to the regulating wheel to oscillate the lever and cause the finger to push a roller sidewise into the spiral groove.

10. In a machine for grinding elongated rollers, a regulating wheel having a spiral groove, a grinding wheel one side of which is slabbed off to make it narrower than the regulating wheel and expose the spiral groove, upper and lower blades extending between the wheels and beyond the grinding wheel, the portions of the blades between the wheels being closer together than the diameter of the rollers and a portion of one blade beyond the wheels being cut away to provide a roller passage, and means for introducing rollers sidewise one at a time through the passage into the spiral groove from the slabbed off side of the grinding wheel.

11. In a machine for grinding elongated rollers, a regulating wheel having a spiral groove, a grinding wheel one side of which is slabbed off to make it narrower than the regulating wheel and expose the spiral groove, a fixed work blade extending between the wheels and beyond the slabbed off side of the grinding wheel, a reciprocating feeding finger movable in the direction of the depth of the groove for pushing a roller laterally over the blade into the groove from the slabbed off side of the grinding wheel.
